VAPOR HEATING SYSTEM

Anthony F. Hoesel, Chicago, Ill., assignor to Peerless of America Inc., Chicago, Ill., a corporation of Illinois

Application July 10, 1944, Serial No. 544,306

6 Claims. (Cl. 237—9)

1

The present invention relates to vapor heating systems and especially relates to such systems whereby the heating of the vapor is accomplished by waste heat such as is rejected in the exhaust discharge of an internal combustion engine.

One of the advantages of my invention is that the maximum vapor pressure is automatically controlled to some predetermined point, irrespective of the amount and/or intensity of the heat generating the vapor and also irrespective of the amount of vapor condensed by means of rejecting its heat to some other medium of a lower temperature than that of the vapor temperature.

Because of the controlled pressures, it is possible to use vapor generators (generally called boilers), vapor condensers (generally called radiators) and connecting vapor conduit means of a considerably lighter construction than that used in conventional systems of the vapor pressure type.

In view of the fact that the vapor pressure is automatically controlled, I find it possible to dispense with the usual self seating type safety valve.

Another advantage stems from the fact that my system is completely closed and, while in a cold state, is under a partial vacuum, which decreases the boiling point temperature, of the contained liquid, so that the transfer of heat begins rather rapidly when the system starts up.

Since many systems, of this type, have to withstand sub-freezing temperatures, my closed system has the advantage of preventing the escape of any anti-freeze fluid having a low boiling point.

In the drawing:

Fig. 1 is an elevational view of a heating system embodying the invention.

Fig. 2 is an elevational view, partly in cross-section, of a pressure control used in the system Fig. 1.

Fig. 3 is a cross-sectional view along line 3—3 of Fig. 1.

Referring to the drawing:

In Fig. 1, I show an exhaust discharge manifold 5 of the type generally used to carry away the hot exhaust gases from a six cylinder internal combustion engine, not shown because the general form and operation thereof is well understood in the art.

An exhaust pipe 6 connects to the manifold 5, as indicated, and serves to carry the hot exhaust gases to a muffler, not shown.

It should be particularly noted that the exhaust pipe 6 has a downwardly leading portion 7 which shall be referred to later. Around the

2

portion 7, I mount a shell 8, which, being of greater inside diameter than the outside diameter of the portion 7, provides an annular space 9, which, during normal operation, is at least partly filled with the vapor generating liquid. Both ends, 10 and 11, of the shell 8, are hermetically sealed, by welding or otherwise, to the exhaust pipe portion 7. The immediate above comprises the vapor generator.

At 12 I indicate a vapor condenser comprising a vapor header 13 having vapor tubes 14 upon which are mounted fins 15 in order to increase the effective heat transfer area.

A motor 16, driving the fan 17, serves to blow air over the exterior surfaces of the tubes 14 and fins 15 thereby heating such air and condensing vapor within the tubes 14.

The tubes 14 drain into a condensate collector 18 from the bottom of which projects a condensate return conduit 19 connected to the low end of the shell 8 as indicated. Immediately below its connection, to the shell 8, the condensate return conduit 19 is provided with a liquid trap 20.

The upper end, of the shell 8, is provided with a vapor conduit 21 leading to the inlet 22 of the pressure control 23 whose outlet 24 is connected to the vapor header 13 by means of the conduit 25.

The vapor condenser 12 is provided with a filler cap 26 whereby the system may be charged with a definite quantity of vaporizable liquid. This quantity is generally slightly in excess of that which will fill the annular space 9.

In Fig. 2, the pressure control 23 comprises a body 27 having a vapor inlet 22 and vapor outlet 24 between which is a valved passage 28 having a seat 29 cooperative with the valve 30 having a guide portion 31 which plays in the bore 32 of the cap 33 threadedly engaging the bore 34 of the body 27.

The valve 30, constantly urged to the valve seat 29 by means of the spring 35, has a stem 36 pressing against a diaphragm 37, which is hermetically sealed to the body 27 and the diaphragm cover 38 as indicated at 39.

The diaphragm cover 38 has a breather hole 40 and a threaded bore 41 in the latter of which an adjusting screw 42 serves to put a proper pressure upon the diaphragm spring 43, mounted upon the diaphragm pusher disc 44, thereby tending to move the valve 30 away from its seat 29.

Having described the various elements of the system, I shall now describe its operation. Assume that the pressures, of the springs 35 and 43, are of such values that a gage pressure of say

4 p. s. i., at the outlet 24, results in the diaphragm 37 moving downwardly and the valve 30 engaging the seat 29. Further assume that the valve 30 is in open position, as shown, at 1 p. s. i. and has an increased throttling action with increase of pressure until 4 p. s. i. is reached at which time the valved passage 29 is completely closed.

We now remove the filler cap 26 and pour in a definite quantity of liquid. The annular space 9 is practically filled and the liquid extends up into the condensate return conduit 19 to approximately the level 48. We now start the source of heat. The liquid, in the annular space 9, starts to boil and vapor issues from the hole in which the filler cap 26 screws. The vapor tends to drive out the air in the system and after a sufficient period of time we replace the filler cap 26. The system is now pressure tight.

During various operations, the vapor condenser 12 will have different condensing capacities. If the motor 16 is stopped then the condensing capacity is at a minimum. If the motor 16 is in operation and the entering air is cold, then the condensing capacity will be at a maximum. Between these two extremes there will be numerous variations in condensing capacity.

During the operation, of the engine rejecting heat to the exhaust manifold 5, there will be varying volumes and heat intensities of the exhaust gases passing through the exhaust pipe 6. Since the amount of heat transfer surface, of the portion 1, is constant, the potential vaporizing capacity thereof will vary accordingly and the actual vaporizing capacity will be a function of both the amount of surface area, of the portion 1, wetted by the vaporizing liquid and the volume and heat intensity of the exhaust gases passing therethrough.

Let us assume a static condition of operation wherein a certain constant exhaust discharge heats the liquid sufficiently to maintain a constant vapor pressure of 1 p. s. i. in the vapor conduit 21. The valve 30 is in the wide open position and the vapor condenser 12 is assumed to reject heat at the same rate that it is generated.

Obviously the vapor flow, through the conduit 21, the pressure control 23, the conduit 25 and the vapor condenser 12, involves a pressure drop. Let us assume that this pressure drop is on the order of 3" water. Under this condition we find that the static liquid level 48 will change to liquid level 49, which presumably is 3" higher than previously.

There now exists a differential of 3" in the liquid levels of the annular space 9 and the condensate return conduit 19.

Let us now suppose that the air, passed over the vapor condenser 12, has increased in temperature and/or decreased in volume. Obviously its heat absorption capacity is decreased and the generated vapor pressure tends to increase. The valve 30 moves towards its seat 29, thereby increasing the flow pressure drop, and the liquid level rises to point 50 of the condensate return conduit 19.

Of course, as the liquid recedes into the condensate return conduit 19, the liquid level lowers in the annular space 9 and with the consequent decreased wetted surface, of the portion 1, the vaporizing capacity is reduced accordingly and automatically to the condensing capacity of the vapor condenser 12.

Assuming a condition of no heat demand, on the part of the vapor condenser 12, and a passage of maximum volume and heat intensity, of ex-

haust gases, through the exhaust pipe 6. We would find that the vapor pressure would quickly rise to 4 p. s. i. and that the valve 30 would be seated. Under this condition the entire liquid volume, in the annular space 9, tends to recede into the condensate return conduit 19 and the condensate collector 18. Since the wetted surface, of portion 1, is practically zero, there can be no further generation of vapor.

As explained previously, the header 13 and the tubes 14 are filled with vapor and, as soon as sufficient vapor condenses, the 4 p. s. i. pressure drops. Since the diaphragm 37 is subject to the pressure, obtaining in the vapor header 13, a drop in the pressure—from the previous 4 p. s. i.—allows the diaphragm 37 to push the valve 30 away from its seat 29 thereby reestablishing a throttled vapor flow, which is accompanied by some liquid again entering the annular space 9 and wetting sufficient of the exhaust pipe, portion 1, to maintain a pressure of somewhat less than 4 p. s. i. and more than 1 p. s. i.

Whenever the system is at rest, it tends to arrive at ambient temperatures, which are considerably lower than the boiling point of the liquid, consequently the previously generated vapor condenses and produces a partial vacuum within the system. To clearly illustrate the advantage of this, let us assume the liquid to be water and the vacuum to be 20 inches mercury. The boiling point of water, at atmospheric pressure, is 212° F., and this temperature must be reached before effective heat transfer vapor (steam in this case) can be forced through a conventional (steam) heating system. With my system—starting with a 20 inch mercury vacuum—we find that the boiling point would be 160° F., therefore my system starts to transmit vapor—for the heat transfer purpose—at a 52° F. lower temperature. This is conducive to a quick warm up of the space to be heated.

While the specific embodiment of the invention is of a preferred form, it is to be understood that there may be various modifications thereof without departing from the spirit and scope of the invention, which is to be limited only to the hereto appended claims.

I claim:

1. A vapor heating system for a body enclosure associated with an internal combustion engine, comprising: an exhaust pipe for the engine, a chamber adapted to contain a body of liquid in its lower portion and to be heated by said pipe, a vapor-condenser disposed above said chamber, for heating the enclosure, a vapor-conduit between the upper portion of said chamber and the upper portion of the condenser, pressure control means in the vapor-conduit for restricting the flow of vapor to the condenser responsively to an increase of vapor pressure in the vapor-conduit, a constantly open condensate return conduit between the lower portion of the condenser and the lower portion of said chamber, the system being sealed against atmosphere and containing a predetermined quantity of liquid.

2. A vapor heating system for a body enclosure associated with an internal combustion engine, comprising: an exhaust pipe for the engine, a chamber adapted to contain a body of liquid in its lower portion and to be heated by said pipe, a vapor-condenser disposed above said chamber, for heating the enclosure, a vapor-conduit between the upper portion of said chamber and the upper portion of the condenser, pressure control means in the vapor-conduit for restricting

the flow of vapor to the condenser responsively to an increase of vapor pressure in the vapor-conduit, a valveless condensate return conduit between the lower portion of the condenser and the lower portion of said chamber, the system being sealed against atmosphere and containing a predetermined quantity of liquid.

3. A vapor heating system for a body enclosure associated with an internal combustion engine, comprising: an exhaust pipe for the engine, a chamber surrounding a portion of the exhaust pipe and adapted to contain a body of liquid in its lower portion and to be heated by said pipe, a vapor-condenser disposed above said chamber, for heating the enclosure, a vapor-conduit between the upper portion of said chamber and the upper portion of the condenser, a pressure control valve in the vapor-conduit for restricting the flow of vapor to the condenser responsively to an increase of vapor pressure in the vapor-conduit, a constantly open condensate return conduit between the lower portion of the condenser and the lower portion of said chamber, the system being sealed against atmosphere and containing a predetermined quantity of liquid.

4. A vapor heating system for a body enclosure associated with an internal combustion engine, comprising: an exhaust pipe for the engine, a chamber adapted to contain a body of liquid in its lower portion and to be heated by said pipe, a vapor-condenser disposed above said chamber for heating the enclosure, a vapor-conduit between the upper portion of said chamber and the upper portion of the condenser, a normally open pressure control valve in the vapor-conduit for restricting the flow of vapor to the condenser responsively to an increase of vapor pressure in the vapor-conduit, a constantly open condensate return conduit between the lower portion of the condenser and the lower portion of said chamber, in the lower portion of which the column of liquid from the chamber is variable in height responsively to variation in pressure in the vapor in the condenser, the system being sealed against

atmosphere and containing a predetermined quantity of liquid.

5. A vapor heating system for a body enclosure associated with an internal combustion engine, comprising: an exhaust pipe for the engine, a chamber surrounding the exhaust pipe and adapted to contain a body of liquid in its lower portion and to be heated by said pipe, a vapor-condenser disposed above said chamber for heating the enclosure, a vapor-conduit between the upper portion of said chamber and the upper portion of the condenser, a pressure control valve in the vapor-conduit for restricting the flow of vapor to the condenser responsively to an increase of vapor pressure in the vapor conduit, a valveless condensate return conduit between the lower portion of the condenser and the lower portion of said chamber, the lower portion of which includes a trap-portion through which the column of liquid from the chamber is variable responsive to variations in pressure in the vapor in the condenser, the system being sealed against atmosphere and containing a predetermined quantity of liquid.
- 10 15 20 25 30 35 40
6. A vapor heating system for a body enclosure associated with an internal combustion engine, comprising: an exhaust-pipe for the engine, a cylindrical chamber surrounding the exhaust-pipe adapted to contain a body of liquid in its lower portion and to be heated by said pipe, a vapor-condenser disposed above said chamber, for heating the enclosure, a vapor-conduit between the upper portion of said chamber and the upper portion of the condenser, pressure control means in the vapor-conduit for restricting the flow of vapor to the condenser responsively to an increase of vapor pressure in the vapor-conduit, a valveless condensate return conduit between the lower portion of the condenser and the lower portion of said chamber, the system being sealed against atmosphere and containing a predetermined quantity of liquid.

ANTHONY F. HOESEL.
